PAUL RICHTER, OF FREITOL, GERMANY

RAMMING MACHINE FOR PREPARATION OF SOLID AND HOLLOW BODIES FROM CERAMIC, CONCRETE, AND LIKE MATERIAL

Application filed May 6, 1931, Serial No. 535,475, and in Great Britain April 10, 1931.

This invention relates to a ramming machine for the preparation of solid and hollow bodies from ceramic, concrete and like materials, and has for its object to provide an improved machine.

According to this invention, the ramming machine consists of a frame supporting a counterweighted slide frame provided with vertical guides, crossheads are mounted upon said guides being spaced apart by a main spring and auxiliary springs, a rammer depends from the lower crosshead, the upper crosshead is connected to a crankshaft and means are provided for raising or lowering the slide frame in relation to the frame during the drive whereby the length of the stroke of the ramming rod can be varied so that when the rammer reaches the upper edge of the mould the striking power is reduced, so avoiding, as often happens, a blow of the rammer on the edge of the mould, causing deformation at the mould edge and in some cases damage to the machine.

The machine is preferably mounted on a stand or carriage in such a manner that the frame is free to revolve and or move horizontally or eccentrically when dealing with certain kinds of work.

The means for raising or lowering the slide frame in relation to the frame preferably consists of a toothed member slidably mounted in guide slots on bolts fixed to the frame, and a lever or operating handle is connected to the said toothed rod moving same into engagement with a locking member integral with the sliding frame whereby the toothed rod and sliding frame can be raised or lowered together while the machine is in operation.

The accompanying drawings illustrate one form of construction, in which, Fig. 1 is a side elevation of the machine with part enlarged for clearness; Fig. 2 is a plan of the carriage; Fig. 3 is a plan of the enlarged part of Fig. 1, Fig. 4 is a front elevation of the locking means for the ground wheel, and Fig. 5 is a front view of Fig. 1.

The frame 1 is provided with vertical guides 2 and a pair of pulleys 3 at the front, 50 and a single pulley 4 at the rear.

Loosely mounted upon the vertical guides 2 is a slidable frame 5 which is suspended from the frame 1 by means of cables 6 passing over the pulleys 3 and then joined together to a single cable, which latter, passes over 55 the pulley 4 at the rear and is attached to a counterweight 7, moving in guides 8 carried by the frame 1.

The slidable frame 5 is provided with vertical guides 9, for receiving crossheads 10 and 11, which are spaced apart by means of a main spring 12 interposed between the crossheads 10 and 11 at the centre, and auxiliary springs 13 and 14 mounted on rods 15 and 16 depending from the upper crosshead 10 and interposed between the lower crosshead 11 and a flange 17 at the base of each rod 15 and 16. A rod 11a depending from the lower crosshead 11 is provided with a rammer 71b.

The upper crosshead 10 is connected to a crankshaft 18 which in turn is provided with a pulley 19 driven from an electric motor 20 by means of an endless belt 21. Said motor 20 is mounted upon a bracket 5a carried by 75 the slide frame 5.

A bar 22 with teeth 23, 24 on each side is provided near each end with a guide slot 25 arranged obliquely across the bar 22 and the ends terminating vertically as shown in Fig. 80 1. A guide pin 26 fixed to the uprights of the frame 1 project through each guide slot 25 and is provided with a lock nut 27, whereby the bar 22 can be held in the middle position. The teeth 23 at the front of the machine are directed downwardly, and the teeth 24 at the rear are directed upwardly, and either set of teeth are adapted to engage with a bridge piece 28 integral with the slide frame 5 by means of pawls 29 or 30 integral 85 with the bridge piece 28.

A hand lever 31 is pivotally mounted on the uprights of the frame 1 and is connected to the bar 22 by means of a link 32 for raising or lowering the bar 22 and slide frame 5 as hereinafter set forth.

A horizontal inverted T-shaped rail 33 is secured to the uprights at each end of the frame 1 and is mounted upon a carrier 34 provided with ground wheels 35, 35a. One 100

of the front ground wheels 35 is provided with locking means for holding the carrier 34 stationary, consisting of recesses 36 cut in the periphery of the wheel for receiving a 5 spring controlled pawl 37 mounted in a frame 38 and provided with a handle 39. The rear ground wheel 35a actuates as the steering wheel, and is controlled by means of a movable rod 40 connected to the head of the 10 forks 41 by means of a link 42.

The carrier 34 is provided with adjustable legs 43 adapted to support the rear of the carrier when the machine is working, and the carrier 34 can be locked to the rail 33 in 15 any suitable manner to prevent lateral movement of the frame 1.

Upon the carrier 34 is a circular framework 44 supporting a turntable 45; extending upwardly from the turntable 45 are cheek 20 plates provided with rollers 47 and 48 between which is interposed the rail 33, whereby the frame 1 can be revolved and or moved horizontally or eccentrically, and the turntable 45 may be held in a stationary position 25 by any suitable manner.

The operation of the machine is as follows:—

The upper crosshead 10 is reciprocated by means of the crankshaft 18 driven from the 30 motor 20, and on the downward movement of the crosshead 10 the main spring 12 and auxiliary springs are compressed as a result of the blow of the rammer upon the material. When the length of the stroke of the rammer 35 is required to be decreased the hand lever 31 is moved downwards causing the toothed bar 22 to first move obliquely when one of the teeth 23 will engage with the pawl 30 on the bridge piece 28, continuing the downward 40 movement of the hand lever 31 the toothed bar 22 is drawn down vertically by the sliding of the guide pin 26 in the vertical extension of the guides 25 on the front of the bar 22, and the slide frame 5 carrying 45 the whole rammer drive is drawn down simultaneously and the rammer 71b is thus pressed against the already rammed upper surface of the material on which it encounters resistance, and at the same time the main 50 spring 12 in consequence of this resistance of the rammer is pressed and prevented from complete swinging and therefor can only impart to the rammer a diminished stroke.

Conversely the arrangement can be employed to raise the ramming mechanism, if this (for instance for getting over excess feeding of the mould with material, or if the ram becomes jammed in the mould) is desired. By upward movement of the hand lever 31 the toothed bar 22 is pushed upwards backwards, until one of the backward teeth 24 engages with the pawl 26. Further upward pressure of the hand lever 31 now effects a lifting of the frame 5 with the whole of the ramming mechanism.

I claim:

1. A ramming machine comprising a frame, a counterweighted slide frame associated therewith, vertical guides fixed to said slide frame, an upper and lower crosshead slidably mounted upon said guides, a main and auxiliary springs, the said crossheads being spaced apart by said main spring and auxiliary springs, a rammer depending from the lower crosshead, means for reciprocating the upper crosshead and means for raising or lowering the slide from in relation to the frame during the drive. 75

2. A ramming machine comprising a frame, a counterweighted slide frame carried by said frame, vertical guides fixed to said slide frame, an upper and lower crosshead slidably mounted upon said vertical guides, a main spring and auxiliary springs spacing apart the crossheads, a rammer depending from the lower crosshead, a toothed bar, guide slots formed near the respective ends of said toothed bar, pins fixed to the frame projecting through said guide slots, a locking member integral with the slide frame engaging with the toothed bar, means for lowering or raising together said toothed bar, means for retaining the toothed bar out of contact with the locking member and means for reciprocating the upper crosshead carried by the slide frame. 80

3. A ramming machine comprising a frame, a counterweighted slide frame carried by said frame, vertical guides fixed to said slide frame, an upper and lower crosshead slidably mounted upon said vertical guides, a main spring and auxiliary springs spacing apart the crossheads, a rammer depending from the lower crosshead, a double sided toothed bar, guide slots formed near the respective ends of said toothed bar, pins fixed to the frame projecting through said guide slots, a locking member integral with the slide frame engaging with the toothed bar, means for lowering or raising together said toothed bar, means for retaining the toothed bar out of contact with the locking member and means for reciprocating the upper crosshead carried by the slide frame. 100

4. A ramming machine comprising a frame, a counterweighted slide frame carried by said frame, vertical guides fixed to said slide frame, an upper and lower crosshead slidably mounted upon said vertical guides, a main spring and auxiliary springs spacing apart the crossheads, a rammer depending from the lower cross head, a double sided toothed bar, the teeth one side being directed downwardly and on the other side directed upwardly, a bridge piece integral with the slide frame, pawls fixed to said bridge piece engaging with the toothed bar, guide slots formed near the respective ends of the toothed bar, pins fixed to the frame projecting through said guide slots, means for re- 115

taining the toothed bar out of contact with the bridge piece, a lever pivoted to said frame and to the toothed bar moving together the slide frame and double sided toothed bar and 5 means for reciprocating the upper crosshead carried by the slide frame.

In witness whereof I affix my signature.
PAUL RICHTER.
